United States Patent Office

Des. 217,853
Patented June 23, 1970

217,853

JEWELRY BOX

Marvin Wernick, Los Angeles, and Irving H. Plone, Playa Del Rey, Calif., assignors to Republic Corporation, Beverly Hills, Calif., a corporation of California

Filed Oct. 21, 1968, Ser. No. 14,089

Term of patent 14 years

Int. Cl. D9—04

U.S. Cl. D9—239

Fig. 1

Fig. 2

Fig. 3

FIG. 1 is a top plan view of a jewelry box showing our new design;

FIG. 2 is a side elevation thereof; and

FIG. 3 is an end elevation thereof.

The side and end opposite those shown in FIGS. 2 and 3 are identical thereto and the bottom is plain and unornamented.

We claim:

The ornamental design for a jewelry box, as shown and described.
